his Atty.*

United States Patent Office.

EZRA SPRINGER, OF DAVIS, ILLINOIS.

Letters Patent No. 101,780, dated April 12, 1870.

IMPROVEMENT IN APPARATUS FOR MOVING CARS.

The Schedule referred to in these Letters Patent and making part of the same

I, EZRA SPRINGER, of Davis, in the county of Stephenson and State of Illinois, have invented certain Improvements in Car-Movers, of which the following is a specification.

Nature and Objects of the Invention.

The nature of my invention relates to a device for starting and moving freight cars on the side track, or in any situation where they are disconnected from the engine; and

The invention consists in a combination of sectors, cams, and levers, conveniently arranged in a suitable frame, whereby great power may be used in starting or moving railway-cars, all constructed and arranged substantially as hereinafter described.

Description of the Accompanying Drawings.

Figure 1 is a side elevation with the rear frame-piece removed.

Figure 2 is a top view.

Figure 3 is a side elevation of one of the frame-pieces.

Figure 4 is a front view of the catches Z and M, of fig. 1.

General Description.

A A are the side or frame-pieces, one of which is shown fully at fig. 3.

B' B" are toothed sectors, connected by arms B B B B, and having a common center, to which they are arranged eccentrically, and through which the axial bolt b passes, having suitable bearings in the frame-pieces A A.

C is a cam-plate, toothed on the face C', gearing with the sector B', and pivoted on the bolt J, the bolt J having bearings in the slots J' J', in the frame-pieces.

D is a bar, pivoted at one end to the end of the cam-plate C, and pivoted, near its center, on the bolt H, the bolt H having bearings in the slots H' H' in the frame-pieces.

M is a forked catch attached to the outer end of the bar D.

R is a rod, pivoted to the upper arm of the sector B" by a stud R", and, at the other end, to the plate C by a stud, R'.

N is a cam-plate, gearing with the sector B', and having a slot S', near its forward end.

S is a bolt passing through the slot S', on which the cam-plate N is pivoted.

P is a rod connecting the cam-plate N and sector B'.

U U' is an angle-plate, pivoted at U" to the end of

the cam-plate N, which projects from between the ends of the side frame-pieces.

V is a loop encircling the angle-plate U U' and pivoted on the bolt U".

The forward end of loop V is formed into a hook, as shown, and the rear end is threaded to receive a set-screw, V'.

W W are plates secured to the plate U'.

Y is a bar, pivoted between the plates W W at its upper end, and carrying a catch or forked bite at its lower end.

X is a lever, secured to the sectors B B'.

The operation of my device is as follows:

The sill, beneath one of the cars, represented in section by lines T, is caught between hook V and plate U, and, by means of the thumb-screw V', the hold is made secure. The fork Z is made to engage with one of the rails, and the fork M is brought down to engage with the same rail, the lever X being in the position shown in the drawings at fig. 1. Now, by drawing the lever X back in the direction of the arrow, it will be plainly seen that the cam-plate N will be projected forward and the bar D projected back, both combining to shove the car forward, then by throwing the lever X forward the whole device will again be brought into position for a repetition of the same operation, the rods R having, when the lever X was thrown forward, served to draw the cam-plates N and C into the position shown in the drawing, thereby sliding and drawing forward the fork M into a new position. The same operation repeated will drive the car forward as far as may be desired.

By means of the power obtained by the cam-plates C and N, and sectors B' B", and toggle-joint formed by the cam-plate C and bar D, one man or boy may easily move or start any car, and by means of all the devices combined the machine may be almost instantly brought into position for another shove.

Claims.

What I claim as new is—

1. The combination and arrangement of the lever X, sectors B' B", cam-plates C and N, and bar D, with the frame-pieces A A and slots J' and S', substantially as described and for the purpose set forth.

2. The rods R and P, when combined with the sectors B' B" and cam-plates C and N, substantially as described and for the purpose specified.

EZRA SPRINGER.

Witnesses:

AMOS CRUM,
THOMAS J. RANEY.
